UNITED STATES PATENT OFFICE.

ALBERT J. LOEPSINGER, OF PROVIDENCE, RHODE ISLAND, ASSIGNOR TO GENERAL FIRE EXTINGUISHER COMPANY, OF NEW YORK, N. Y., A CORPORATION OF NEW YORK.

METHOD FOR PREPARING GLASS BULBS FOR AUTOMATIC SPRINKLERS.

1,199,090.

Specification of Letters Patent. Patented Sept. 26, 1916.

Application filed July 3, 1912. Serial No. 707,472.

To all whom it may concern:

Be it known that I, ALBERT J. LOEPSINGER, of the city and county of Providence and State of Rhode Island, have invented a certain new and useful Method for Preparing Glass Bulbs for Automatic Sprinklers; and I do hereby declare the following specification taken in connection with the accompanying drawings, forming a part of the same, to be a full, clear, and exact description thereof.

In an application of even date, Serial No. 707,467, I have shown and described an automatic sprinkler of that type which embodies in its construction a frangible vessel having expansible contents and which is caused to be opened by the expansive or explosive force of the contents of such frangible vessel induced by the action of heat. 20 The preferred form of frangible vessel for use in such an automatic sprinkler consists of a glass bulb with an elongated neck.

The present invention relates to the preparation of such glass bulbs for use in automatic sprinklers of the type referred to, and the invention consists in a novel method of preparing such bulbs, which method is illustrated in the accompanying drawings and will be described in connection therewith.

30 Referring to the drawings, Figures 1 to 3 inclusive are sectional views of a bulb illustrating the several steps of the method hereinafter described, Fig. 2 showing the bulb placed in a closed receptacle, and Fig. 4 being a sectional view of an apparatus employed in connection with sealing the bulb.

The frangible vessel comprises a glass bulb 1 provided with an elongated hollow neck 2. The bulb and its neck are first completely filled at normal temperature, as for example 70° Fah., with a liquid containing a quantity of gas in solution, and preferably with an ammonia gas solution, as shown in Fig. 1. The bulb with its contents is then placed in a closed receptacle 3, shown in section in Fig. 2, which receptacle is preferably provided with suitably shaped holding devices 4, 4, as shown. Pressure is then applied within this receptacle and the bulb 40 and its contents therein are then heated up to a desired high temperature, as for example 160° Fah. The expansion of the contents of the bulb under the action of the heat applied causes a certain amount of the liquid

contents to flow out of the open end of the neck, but the presence of the pressure within the receptacle serves to prevent the escape of the gas with the liquid and causes the gas to be retained within the bulb. The bulb and its neck after this application of heat remain completely filled with the ammonia or other solution, as shown in Fig. 2. The bulb thus completely filled with the ammonia or other solution is then removed from the closed receptacle and cooled to normal temperature, as for example 70° Fah., which will cause a corresponding lowering of the level of the liquid column in the neck of the bulb and bring the level of such column to a certain point within the neck of the bulb, as shown in Fig. 3. Inasmuch as the bulb and its neck were completely filled with the ammonia or other solution at 160° Fah. when in the closed receptacle they will be again entirely filled with the solution whenever the bulb and its contents are again subjected to a temperature of 160°.

Referring now to the sealing of the bulbs, this may be done in another closed receptacle under pressure, and a suitable apparatus for this purpose is shown in Fig. 4 of the drawings, which figure is a side view of such apparatus partly in section. This apparatus and the method of sealing the bulbs will next be described.

The apparatus referred to comprises a receptacle 4' having an opening in its upper wall through which the bulb may be placed in position within the receptacle. The opening referred to is tightly closed by a cover 5 which is held securely in place by a screw 6 working in a bracket 7 rigidly secured to the body of the receptacle. Suitably shaped holding devices 8, 8 are provided within the receptacle to receive and hold the bulb during the process of sealing. Communicating with the interior of the receptacle is a pipe 9 leading from a pump or compressed air reservoir (not shown) whereby the interior of the receptacle may be filled with air under pressure. The pipe 9 is provided with a valve 10 for controlling the admission of air to the receptacle. 11 is a relief valve which is to be set or adjusted at the pressure desired to be maintained within the receptacle and to prevent any greater pressure therein. 12 is a burner secured to the end of a pipe 13. The pipe 13 extends through the end

wall of the receptacle and through a stuffing box 14, and so that said pipe and the burner 12 carried thereby may be moved toward and from the bulb to be sealed when 5 the same is in position within the receptacle. The outer end of the pipe 13 is connected by a link 15 to one end of a lever 16 pivoted at 17 to a bracket 18 secured to the wall of the receptacle. Preferably the bracket is 10 provided with projecting lugs 19 and 20 adapted to be engaged by the bosses 21, 22, respectively, formed on the lever 16 to limit the inward and outward movements of the burner 12.

15 Communicating with the pipe 13 outside of the receptacle is a pipe 23 leading to a supply of compressed air, and communicating with said pipe 23 is a pipe 24 leading to a gas supply, whereby a mixture of gas 20 and air is supplied to the pipe 13. A valve 25 in the pipe 23 controls the admission of the mixture of gas and air to the pipe 13 and the burner 12. The pipes 23 and 24 are to be connected with flexible pipes (not 25 shown) in order to permit the to and fro movements of the pipe 13 and the burner 12.

The operation of the apparatus above described will be readily understood. Assuming the burner 12 to be lighted, and to be 30 in its outer or withdrawn position, the cover of the receptacle is removed and the bulb to be sealed is placed in the holding devices 8, the arrangement of said devices being such that the end of the neck of the bulb will be 35 held substantially in line with the burner 12. The cover 5 is then secured in place and the valve 10 is opened to admit compressed air into the receptacle, preferably up to the pressure determined by the relief valve 11. The 40 lever 16 is then moved to bring the boss 21 thereon into engagement with the lug 19, thereby moving the burner 12 toward the neck of the bulb and into the position shown in Fig. 4, thereby bringing the flame into 45 position to impinge upon the end of the neck of the bulb, which by the action of the heat will be fused and closed and the bulb thereby hermetically sealed. The air-pressure within the receptacle will prevent any material escape of gas during the process of sealing.

50 Preferably an opening 26 is provided in one of the side walls of the receptacle in line with the bulb with a pane of glass 27 55 in said opening through which the operator may note the progress of the fusing and ob-

serve when the bulb has been properly sealed. The lever 16 is then moved to withdraw the burner, the amount of such movement being determined by the engagement 60 of the boss 22 with the lug 20. The cover is then taken off, the bulb removed from the receptacle, another put in its place, and the operations above described repeated. The receptacle 4 may be of any desired size to receive any desired number of bulbs, all of which bulbs may be sealed simultaneously, a separate burner being preferably provided for each bulb to be sealed.

65 By the method of preparing the bulbs above described the ammonia or other gas solution is prepared outside of the bulb and may be so prepared with a definite prescribed ratio and the ammonia or other gas solution so prepared is placed in the bulb 75 at normal temperature.

I make no claim herein either to the method of sealing the bulbs above described, the same forming the subject of a divisional application, Serial No. 83,682, filed March 80 11, 1916, or to the apparatus shown and described for use in connection with the sealing of the bulbs, which apparatus forms the subject of my application, Serial No. 707,473.

What I claim as my invention and desire 85 to secure by Letters Patent is:

1. The method of filling and sealing glass bulbs which consists in first filling the bulb with a gas solution at normal temperature, then placing the bulb in a closed receptacle, 90 then introducing pressure into said receptacle and there heating the bulb and its contents up to a desired high temperature, thereby permanently expelling a quantity of the liquid from the bulb, then cooling the 95 bulb and its contents and then sealing said bulb.

2. The method of filling and sealing glass bulbs which consists in first filling the bulb with a gas solution at normal temperature, 100 then placing the bulb in a closed receptacle, then introducing pressure into said receptacle and there heating the bulb and its contents up to a desired high temperature, thereby permanently expelling a quantity of liquid 105 from the bulb, then cooling the bulb and its contents and then sealing the bulb under pressure.

ALBERT J. LOEPSINGER.
